UNITED STATES PATENT OFFICE.

CHARLES MURRAY AND FRANK FLEURY, OF SPRINGFIELD, ILLINOIS.

DESIGN FOR AN ELECTRIC LAMP.

SPECIFICATION forming part of Design No. 35,326, dated November 26, 1901.

Application filed October 5, 1901. Serial No. 77,746. Term of patent 14 years.

To all whom it may concern:

Be it known that we, CHARLES MURRAY and FRANK FLEURY, citizens of the United States of America, and residents of Springfield, county of Sangamon, and State of Illinois, have invented and produced a new and original Design for Electric Lamps, of which the following is a specification.

In the accompanying drawings, Figure 1 is a side elevation of an electric lamp, showing our design. Fig. 2 is a section through the glass globe, showing the reflecting-surfaces; and Fig. 3 is a plan.

In the said drawings, S is a metallic socket, within which is held a glass globe G, one part of which is formed into a circular flange F. That part of the flange F which is marked F' is silvered on the inside, so as to make a reflector of it. Within the globe G and adjacent to the flange F is a reflecting-disk R, so located that the said disk and the reflecting-

surface F' constitute a continuous reflecting disk, the surface of which is curved, as shown in Fig. 2. From points R' in the disk R rises the filament C, which extends in a spiral form 25 over the reflecting-face of said disk.

The leading or material features of our design consist of the globe G, provided with a disk-like reflecting-surface F' and R and having disposed over the reflecting-surface the 30 spirally-formed filament C.

What we claim is—

The design for an electric lamp as herein shown and described.

Signed at Springfield, Illinois, this 1st day 35 of October, 1901.

CHARLES MURRAY.
FRANK FLEURY.
